UNITED STATES PATENT OFFICE.

RADO B. CATTON AND IRA C. CATTON, OF BRIMFIELD, ILLINOIS.

GRAIN-DOOR.

972,505.

Specification of Letters Patent. Patented Oct. 11, 1910.

Application filed December 18, 1908. Serial No. 468,133.

To all whom it may concern:

Be it known that we, RADO B. CATTON and IRA C. CATTON, citizens of the United States, residing at Brimfield, in the county 5 of Peoria and State of Illinois, have invented certain new and useful Improvements in Grain-Doors, of which the following is a specification, reference being had therein to the accompanying drawing.

This invention relates to grain-car doors, and has for its object to provide an improved grain-car door composed of interlocking sections, which may be opened independently to facilitate the loading or unloading of the car.

In carrying out the object of the invention generally stated above it will, of course, be understood that the essential features thereof are susceptible of changes in details 20 and structural arrangements, but a preferred and practical embodiment of the same is shown in the accompanying drawings wherein—

Figure 1 is a perspective view of a portion of the interior of a car showing the same equipped with the improved door. Fig. 2 is a similar view of the exterior of a car. Fig. 3 is a longitudinal sectional view of a car showing the door sections in an open condition. Fig. 4 is a vertical sectional view taken on the line 4—4, Fig. 1. Fig. 5 is a similar view taken on the line 5—5 of Fig. 2, but viewed from the interior of the car. Fig. 6 is a detail perspective view of the 35 slide for the supplemental opening of one of the sections of the door. Fig. 7 is a detail sectional view of a portion of one of the upper sections of the door showing the hinge connection between the same and the 40 door frame.

Like characters of reference designate corresponding parts in the several figures of the drawings.

Referring to the said drawings, 1 designates the side walls of a car, 2 the floor, and 2^a the door frame, all of which are of the usual construction common to the well-known box cars.

The improved interior door for the car 50 consists of a plurality of metal sections, the lower one 3 of which has one of its lower corners pivotally connected with an angular bracket 4 carried by the floor 2 of the car adjacent to one side of the door frame 55 2^a. Said section 3 has its body provided with a plurality of regularly spaced apart

strengthening crimps or corrugations 5 and is held in a closed position by means of a spring latch or keeper 6 carried by the door frame intermediate of its longitudinal 60 length and which has a slideable engagement between two spaced apart fastening loops 7. Said latch or keeper is preferably provided with an outstanding portion 8 formed by crimping its body, said outstanding portion 65 forming a stop which engages with one or the other of said loops 7 to limit the locking or unlocking movement of the latch. The door frame is also provided at its lower corner with an angular strap 9 the free end 70 of which engages with the lower edge of said section to assist in retaining said section in a closed position, in an obvious manner. The lower portion of the section 3, between the first two strengthening ribs or 75 corrugations, is provided with an elongated, horizontally extending opening 10, the upper and lower edges on their interior sides being provided with a bracing strip or strips 11 and overhanging guide strips 12, which 80 project well beyond both ends of said slot, as shown more clearly in Figs. 1 and 3, and serve to retain between them a sliding door 13 provided with an operating handle or knob 14 that projects beyond said opening, 85 so that said door may be opened or closed from the exterior of the car. The section 3 is also provided with a hand grip 15 at its upper portion which facilitates the opening or closing of said section. To open said 90 section 3, it is thrown back on its pivotal connection with the floor of the door, until its side edge rests on the said floor, as shown in Fig. 3. Normally the connection of said section will be sufficient to retain said section in its open position, but as an additional safeguard, the side of the car may be provided with a spring loop 16 beneath which one portion of said section passes 95 when thrown to its open position.

The upper edge of the section 3 is provided with an outstanding integral reinforced tongue 17 which has an interlocking engagement with a groove 18 of an intermediate door section 19. Said section 19 is 100 also provided with a strengthening rib or corrugation 21 and has one of its ends outwardly to form pivot ears 22 which engage with a hinge pin 23 of a hinge leaf 24, carried by the door frame on the side opposite 105 to that which carries the hinge connection for the lower section 3. The said intermedi-

ate door section 19 has its upper edge provided with an outstanding integral tongue 25 similar to the one shown on the upper edge of the section 3, and which is engaged by a groove 26 on the lower edge of an upper door section 27, said engagement being an interlocking one similar to the interlocking engagement between the section 3 and the section 19. The section 27 also has its end outturned to form hinge ears 28 for pivotal engagement with the hinge pin 23 of the leaf hinge 24, referred to above.

Both the upper section and the intermediate section have their inner sides provided with a latch carrying loop 29 which may be formed by slitting the material of which they are formed and bending the same outwardly, with which the eye of a latch, or hook, 30 is connected, and which is adapted 15 to engage with a keeper or eye 31 carried by the door frame. The lower section 3 may also be provided with a loop 32 that is formed in the body thereof in the same manner as the loops of the other two sections are formed, and which is engaged by 20 a hook or latch 33 carried by the door frame.

It will be understood from the foregoing that when the door sections are in the closed 30 position there is no danger of any of the grain leaking from the car, as all connections between the sections are interlocking ones, which close all meeting edges. And it will also be seen that as all of the sections 35 have an independent hinge connection with the car, they may be closed one at a time as the car is gradually loaded. To unload the car, the upper section is thrown to the position shown in Fig. 1, which permits the 40 upper part of the grain to be removed. Then the intermediate section is opened, and finally the lower section is opened.

The door carried by the lower section may be used for sampling purposes, as has been heretofore stated, or it may be used to discharge the grain from the car in limited quantities, or it may be used to relieve the pressure of the grain from the door before the upper section is opened.

As has been before stated, the door sections are of metal each section being preferably formed from a single sheet, and operated on by a shaping machine to form the desired strengthening ribs or corrugations, and also to form the end pivot ears. It will be seen that by forming the sections from a single piece of metal the same may be produced cheaply and economically so far as material is concerned.

Claim:—

In a door of the class described, the combination with a door opening, of a door for said opening including a sheet-metal leaf pivoted at one of its lower corners to swing in a vertical plane and provided on the edge 65 coming uppermost when closed with a flange extending away from the door opening, and a second sheet-metal leaf pivoted at one edge to swing in a horizontal plane and provided with a grooved flange at its 70 lower edge to engage over the flange of the first leaf when the door is closed, whereby a bearing is provided between the edges of said leaves and the first mentioned leaf locked from opening by the closing of the 75 second leaf.

In testimony whereof we hereunto affix our signatures in presence of two witnesses.

RADO B. CATTON.
IRA C. CATTON.
